Primary Examiner — Keli L Hill*(74) Attorney, Agent, or Firm* — Sand & Sebolt(57) **CLAIM**

The ornamental design for the speaker stand, as shown and described.

DESCRIPTION

FIG. 1 is a top perspective view of a first embodiment of the speaker stand in accordance with my design;

FIG. 2 is a bottom perspective view of the first embodiment of the speaker stand in accordance with my design;

FIG. 3 is a top perspective view of a second embodiment of the speaker stand in accordance with my design;

FIG. 4 is a bottom perspective view of the second embodiment of the speaker stand in accordance with my design;

FIG. 5 is a top plan view of the first and second embodiments of the speaker stand in accordance with my design;

FIG. 6 is a bottom plan view of the first and second embodiments of the speaker stand in accordance with my design;

FIG. 7 is a front elevation view of the first embodiment of the speaker stand in accordance with my design;

FIG. 8 is a side elevation view of the first embodiment of the speaker stand in accordance with my design;

FIG. 9 is a front elevation view of the second embodiment of the speaker stand in accordance with my design; and,

FIG. 10 is a side elevation view of the second embodiment of the speaker stand in accordance with my design.

The broken lines illustrate portions of the speaker stand which form no part of the claimed design.
